CLAIM

The ornamental design for a lavatory cleaning device, as shown and described.

DESCRIPTION

FIG. 1 is a perspective view of a lavatory cleaning device in accordance with my new design;

FIG. 2 is a front elevational thereof;

FIG. 3 is a right side elevational view thereof;

FIG. 4 is a bottom plan view thereof;

FIG. 5 is a rear elevational view thereof;

FIG. 6 is a left side elevational view thereof; and,

FIG. 7 is a top plan view thereof.

The broken lines in the figures are for illustrative purposes only and form no part of the claimed design.
